UNITED STATES PATENT OFFICE

CHARLES I. LONGENECKER, OF MILWAUKEE, WISCONSIN, ASSIGNOR TO CHAIN BELT COMPANY, OF MILWAUKEE, WISCONSIN, A CORPORATION OF WISCONSIN

DIAPHRAGM PUMP

Application filed April 23, 1928. Serial No. 272,079.

This invention relates to diaphragm water pumps and has for one of its objects to provide an apparatus of this character which will be simple in construction, comparatively inexpensive to manufacture, and more efficient in use than those which have heretofore been proposed.

A further object of the invention is to provide a pump of the class described so constructed and arranged as to facilitate ready access to the diaphragm for the purpose of inspection and renewal when the latter becomes worn or ineffective.

15 A still further object of the invention is to provide a water pump of the diaphragm type in which the diaphragm is provided with a discharge port controlled by a valve which is maintained submerged and water-sealed during the operation of the pump.

20 With the above and other objects in view, which will appear as the description proceeds, the invention consists in the novel details of construction and combinations of parts more fully hereinafter described and particularly pointed out in the appended claim.

Referring to the accompanying drawings forming a part of this specification in which like reference characters designate like parts in all the views:

Fig. 1 is a side elevational view of a pump constructed in accordance with the present invention.

Fig. 2 is a central longitudinal sectional view of the pump shown in Fig. 1.

Fig. 3 is an end elevational view partly in section as seen from the right of Figs. 1 and 2. Fig. 4 is a transverse vertical sectional view taken approximately on the plane indicated by the line 4-4 of Fig. 2, and

Fig. 5 is a side elevational view of the pump showing the parts in inoperative position for inspection and renewal of the diaphragm.

45 In the said drawings numeral 10 indicates a suitable supporting frame upon the transverse members 11 of which is mounted the base member 12 of the pump. This base member is hollow to provide an intake chamber
50 13 having an inlet port 14 controlled by a

suitable check valve 15 (see Fig. 3). This check valve may be of any suitable form and is here shown as of the gravity actuated type comprising a suitable flexible member 16 secured as at 17 to the upper portion of the inlet member and provided with suitable weights 18 and 19 adjacent its lower portion for facilitating the gravity closing of the valve. 55

The upper portion of the base member 12 is open and the said member is surmounted by the pump top member 20, which is adapted to be secured in place by suitable bolts 21 and nuts 22 clearly shown in Figs. 1 and 3. The top member 20 is also hollow to provide an outlet chamber 23, and a flexible diaphragm 24 of rubber, metal or other suitable material is normally interposed between the top member 20 and base member 12 with its outer edge clamped between the said members, as shown in Fig. 2. The said diaphragm 24 is perforated at its center to provide a port or discharge 25, which port is controlled by an upwardly opening valve 26. Means are provided for flexing the diaphragm 24, comprising a diaphragm connecting rod 27, which is provided with a pair of downwardly extending pins or studs 28, the lower portions of which pass through suitable spacing members or washers 29 and 30, as well as through the diaphragm 24, and are secured by nuts 31. The valve member 26 is provided with a pair of openings 32 through which the pins or studs 28 pass, whereby the said studs serve as guides for the said valve as will be readily understood.

The diaphragm connecting rod 27 extends outwardly through an opening 33 in the upper wall of the top member 20 and is pivotally connected by a pin 34 with one end of a lever or rocker arm 35 which is pivotally mounted as at 36 in ears 37 carried by the top member 20. The other end of the lever or rocker arm 35 is pivotally connected by a movable pin 38 with a rod or link 39 which passes into a transmission housing 40 where its lower end is pivotally connected as at 41 to a lever 42 pivoted as at 43 to the said housing. Said lever 42 has pivotally connected to it as at 44 a connecting rod 45, the lower

end of which is provided with an eccentric strap 46 engaging around an eccentric 47 mounted upon a transverse shaft 48. Said shaft 48 carries a worm wheel 49 which is driven by a worm 50 carried by a shaft 51, which is connected through a suitable clutch mechanism 52 with the fly wheel 53 of an internal combustion engine or any other suitable source of power not shown. The lower part of the transmission housing 40 is adapted to be partially filled with lubricating oil whereby the transmission will be effectively lubricated and rendered noiseless. In order to prevent the entrance of foreign matter into the transmission housing where the connecting rod 39 enters the said housing, I prefer to provide an outwardly extending tube or sleeve 55 surrounding the connecting rod 39 and a telescoping sleeve or tube 56 carried by the said connecting rod as clearly shown in Fig. 2, which construction will effectively prevent the entrance of dust, water, and the like into the transmission housing.

It is very advantageous in pumps of this character, especially where water is being elevated a relatively great distance to prevent the discharge valves, such as 26, from passing air back into the intake chamber 13 in the event the valves should become dirty or should stick in a partially open position. In order to accomplish this desirable result in the present instance the discharge spout 57 of the top member 20 is raised to such a position that its lowermost wall 58 is in a plane higher than that ever assumed by the discharge valve 26. It results from such a construction that a pool of water will be always maintained in the discharge chamber 23 above the diaphragm 24, the level of which will be that of the wall 58 of the discharge spout and since this water level is higher than any plane ever assumed by the valve 26 it follows that the said valve will at all times be water sealed. Should the valve become fouled, or should it stick in a partially opened position upon the up-stroke of the diaphragm flexing means, water and not air will leak past the said valve into the intake chamber 13 and the suction of the pump will thereby be preserved.

In pumps of this type it is frequently necessary to replace the flexible diaphragms such as 24 and the present invention, as above stated, contemplates means for facilitating access to these diaphragms for such replacement. To this end means are provided whereby the top member 20, together with the diaphragm or diaphragm flexing means, 27 and 35, carried by said top member, may be readily swung to one side, as shown in Fig. 5, thereby exposing the diaphragm to view and placing it in a position whereby it may be readily removed and renewed. This

is accomplished by providing the detachable clean-out plate 60, which normally closes the clean-out opening 61 of the pump base 12, with an enlargement or projection 62 which is adapted to serve as a pivot about which the top member 20 may be swung from the position shown in Fig. 1 to that shown in Fig. 5. The plate 60 is provided with a bifurcation or groove 63 which receives a web 64 formed upon the top member 20 and which serves to prevent lateral movement of the top member relative to the base member when the parts are in the position shown in Fig. 5.

In order to swing the top member 20 and its associated parts to the position shown in Fig. 5, it is of course necessary to disconnect the diaphragm-flexing mechanism from the power transmission mechanism and this is accomplished by relieving the set screw 65 and sliding the connecting pin 38 to the position shown in Fig. 4, whereby the rocker arm 35 is disconnected from the connecting rod 39 as will be readily understood.

During the movement of the parts to the inoperative position shown in Fig. 5 it is desirable to maintain the diaphragm and flexing mechanism against relative movement and this is accomplished by inserting a pin or rod 66 between the upper surface of the pump top member 20 as shown in dotted lines in Fig. 2 and in full lines in Figs. 1 and 5, which pin will serve to wedge the parts in the position shown and prevent them from moving around while the diaphragms are being changed.

The general operation of the pump is similar to the ordinary diaphragm pumps, it being understood that upon power being applied to the diaphragm-flexing mechanism 27 through the power transmission the said flexing mechanism will be reciprocated, thereby flexing the diaphragm 24, which action serves upon the upward stroke to close the valve 26 and create a suction in the intake chamber 13, while on the downward stroke the valve 26 is opened, thereby permitting water in the intake chamber 13 to pass through the port 25 into the discharge chamber 23. As above stated owing to the raising of the discharge spout 57, a pool of water is always maintained above the diaphragm 24, which serves to water-seal the valve 26 and prevent the entrance of air into the intake chamber, should the said valve stick in an open position.

While one form of the invention has been illustrated and described it is obvious that those skilled in the art may vary the details of construction as well as the precise arrangement of parts, without departing from the spirit of the invention and therefore it is not wished to be limited to the above disclosure except as may be required by the claim.

What I claim is:

In a diaphragm water pump, a base member; a top member; a flexible diaphragm normally clamped between said base and top members; means carried by said top member connected to said diaphragm for flexing the latter; power means for actuating said flexing means; a readily detachable connection between said actuating means and said flexing means; and a removable clean-out plate carried by said base member provided with a portion for pivotally engaging said top member, whereby said top member, diaphragm and flexing means may be readily swung to an inoperative position to facilitate access to said diaphragm.

In testimony whereof I affix my signature.

CHARLES I. LONGENECKER.
